UNITED STATES PATENT OFFICE.

JOSEPH BEAUCHESNE, JR., OF WATERVILLE, MAINE.

HOSE-COUPING.

1,012,121.

Specification of Letters Patent. Patented Dec. 19, 1911.

Application filed May 26, 1910. Serial No. 563,579.

To all whom it may concern:

Be it known that I, JOSEPH BEAUCHESNE, Jr., a citizen of the United States, and a resident of Waterville, in the county of Kennebec and State of Maine, have invented certain new and useful Improvements in Hose-Couplings, of which the following is a full and complete specification.

My invention relates to devices for coupling fire-hose to water-plugs, and has for its object the provision of a device by which the hose may be coupled to the plug instantaneously by simply pushing the coupling-sleeve on the plug connection; and it consists in the provision of a plurality of spring-actuated jaw members having serrations or teeth to engage the threads of the plug connection, the outer ends of the jaw members being beveled to cause them to retreat into the coupling-sleeve when it is being placed on the connection. The back sides of the jaw members are formed with projections that engage inclined ears on the inner side of a ring mounted on a sleeve to move the jaw members from engagement with the plug connection in uncoupling the hose.

My invention will be described herein-after in detail and illustrated in the accompanying drawings, in which—

Figure 1 is a side view of my improved coupling-sleeve, showing it in position on plug connection and a fragment of hose in place; Fig. 2, a cross-section of the sleeve through the jaw members; Fig. 3, an end view with the cover plate 19 removed; Fig. 4, a detail view of the operating-ring; Figs. 5 and 6, detail views of one of the jaw members; and Fig. 7, a detailed sectional view of the interior of the coupling-ring showing the means for actuating the clamping members out of clamping position.

Similar reference characters indicate corresponding parts in the drawings throughout the several views.

My improved coupling consists of a sleeve 1, threaded at one end, as shown at 2, to receive the end of the hose A, while its other end is formed with a cylindrical chamber 3 to receive the threaded connection B employed on fire-plugs.

The wall of the chamber 3 is provided with a plurality of openings 4, of which there should be four or more, having their

outermost and innermost sides beveled on parallel planes, as shown at 5, and 6, respectively, and 7 indicates clamping or jaw members formed with serrations or broken threads 8 to engage the threads on the plug connection B, the inner and outer sides of the clamping members being beveled, as shown at 9 and 10, to engage the beveled surfaces 5 and 6 in the openings 4.

11 indicates angular pins secured to the sleeve 1, and 12 coil-springs secured to said pins and clamping members 7, said springs normally tending to move the clamping members into engagement with the threaded connection B. The outer portions of the serrated side of the members 7 are beveled, as shown at 13, so that in placing the sleeve in position on the connection B the clamping members are moved back to permit the sleeve to be placed on the connection, and when the sleeve is in position the springs 12 move the clamping members inwardly into engagement with the connection B.

The rear sides of clamping members 7 are formed with projections 14, and 15 indicates a ring revolvably mounted on sleeve 1 and having inclined flanges 16 on its inner side to engage projections 14 and move the clamping members 7 out of a clamping position, said ring being provided with laterally extending lugs 17 to receive the ordinary wrench used in coupling and uncoupling hose.

18 indicates coil-springs connecting sleeve 1 and ring 15 to hold the flanges 16 normally out of engagement with projections 14.

19 indicates an annular plate mounted on threaded shoulder 20 to close the opening between ring 15 and sleeve 1.

It will be understood that as the connection B is ordinarily constructed it is threaded to receive the coupling-sleeves as ordinarily constructed and in my improved coupling I have formed the serrations on broken threads 8 on the members 7 so as to fit the threads of the connection as ordinarily constructed, but it will be apparent that after my coupling has been adopted the connection and members may be formed with tongues and grooves or other suitable construction, so that I do not limit myself to the construction shown except where specifically stated in the claims appended hereto.

21 indicates a gasket between the inner end of connection B and shoulder 22 in the sleeve 1.

Having thus described my invention, what I claim is:—

1. In a hose-coupling, a sleeve having openings in its side walls with their outermost and innermost edges beveled on parallel planes, coupling members mounted in said openings and having their edges beveled to correspond with the beveled edges of the openings, angular pins secured to the sleeve, springs secured to said pins and engaging the coupling members to hold them normally in clamping position, and means to actuate said coupling members into uncoupling positions against the resistance of said springs, substantially as shown and described.
2. In a hose-coupling, a sleeve having openings in its side walls with their outer-

most and innermost edges beveled on parallel planes, coupling members mounted in said openings and having their edges beveled to correspond with the beveled edges of the openings, angular pins secured to the sleeve, springs secured to said pins and engaging the coupling members to hold them normally in clamping position, inclined projections on the rear sides of the coupling members, and a ring revolvably mounted on the sleeve and provided with inclined flanges to engage the inclined faces of said projections, substantially as shown and described.

In witness whereof, I have hereunto set my hand in presence of two subscribing witnesses.

JOSEPH BEAUCHESNE, JR.
